UNITED STATES PATENT OFFICE

EUGENE HAHN, OF PHILADELPHIA, PENNSYLVANIA

ASH DISCHARGING DEVICE

Application filed November 30, 1926, Serial No. 151,743. Renewed May 25, 1932.

This invention relates to improvements in ash hoppers, and more particularly in that type of hopper adapted to receive ashes directly from the grates of the boilers or furnaces and to deliver them periodically either to vehicles drawn beneath the hoppers or to conveyers by which the ashes are conducted to suitable points of discharge.

The principal object of the invention is to provide a novel form of hopper affording certain material advantages, hereinafter enumerated, over hoppers of this type as constructed prior to my invention.

A more specific object of the invention is to provide novel and advantageous means for collecting and carrying off the water used for quenching the ashes.

Another object of the invention is to provide novel means for providing the inner surface of the hopper with heat and acid resisting lining.

A still further object of the invention is to provide novel means for agitating the ashes within the hopper to insure a free flow to the outlet.

The invention further contemplates novel means for coordinating the dump plates controlling the passage of ashes into the hopper and the valves controlling the flow of water from the quenching apparatus.

In the attached drawings:

Figure 1 is a plan view of the hopper made in accordance with my invention;

Fig. 2 is a side elevation of the hopper;

Fig. 3 is a fragmentary front elevation showing the details of the discharge port;

Fig. 4 is a section on the line 4-4, Fig. 3, and

Fig. 5 is a fragmentary sectional view illustrating the details of the mechanism coordinating the ash dump plate and the quenching means.

Referring to the drawings, the hopper as shown in the present instance is of semi-octagonal form. The hopper may be built of a plurality of plates secured together at the edges in accordance with the principle set forth in my copending application, Serial Number 13,876. In this form of invention, I have disclosed a tank or a hopper made up of

a plurality of plates adapted to be united at their edges either by means of integral flanges or by overlapping members, as shown.

In the present instance, the bottom of the tank, as clearly illustrated in Fig. 2, is formed at an inclination to the horizontal of approximately 45°, and the discharge port of the hopper is placed at the bottom of this inclined wall, as clearly illustrated.

In Fig. 4, the discharge opening is designated by the reference numeral 10, and from this opening extends an inclined chute 11. This chute, which in the present instance, is rectangular in form, is adapted to carry at its lower end a suitable gate structure controlling the flow of ashes from the hopper, but since this gate structure may take a variety of forms and constitutes no part of the present invention, it has not been illustrated. In the bottom of the chute 11 is a transverse opening 12 which as shown in Fig. 3 extends completely across the width of the chute, and extending downwardly from this opening 12 is a funnel-like structure 13 terminating at its bottom in a restricted opening 14 which connects in the present instance with a pipe 15 extending to a suitable drain.

Supported in the opening 12 and constituting a part of the floor or bottom wall of the chute 11 is a slotted grate member 16, the slots 17 of this member extending substantially the entire length of the member and accordingly transversely completely across the chute. The slots 17 are so proportioned as to prevent passage therethrough of any substantial sizes of ashes or other material passing through the chute 11, but offer a ready passage for water and fine ash dust, as hereinafter more fully set forth. The slots preferably are flared or widened toward the bottom.

At the top of the hopper and extending completely therearound is a water pipe 18, from which short branches with nozzles 19 project into the interior of the hopper through suitable openings 20 provided for their reception. The pipe 18 is connected to a line 21 with a suitable source of water supply, and a valve 22 controls the flow of water from the source to the said pipe 21. It

will be apparent that when the valve 22 is open, water will be projected through the nozzles 19 into the top of the hopper from all sides, the projection preferably being in the form of a spray which will permeate and quench the hot ashes and cinders entering the hopper. This water after passing downwardly through the ashes eventually flows into the chute 11 and through the slots 17 in the grate member 16, thereafter passing off to a suitable drain through the pipe 15.

As previously set forth, this hopper is adapted to receive ashes directly from the grates of boilers or furnaces, and for this purpose it is customary to mount the hopper directly below the ash pit of the furnace so that the ashes may drop from the ash pit directly into the hopper. Such an arrangement I have illustrated more or less diagrammatically in Fig. 5. In this instance, I have illustrated at 23 the lower end of an automatic stoker which feeds into an opening 24 controlled by a dump plate 25. This plate 25 when elevated, as illustrated in full lines, effectually closes the opening 24, but when dropped to a position as shown in broken lines permits ashes to fall into the hopper which, as shown, is positioned directly below said opening. The plate 25 is controlled in the present instance through lever and link mechanism 26 by a manually operated bar 27, and this bar also connects through a connecting rod 28 and a lever 29 with the valve 22. With the lever 29 in the position shown in full lines, the valve 22 is closed, and it will be noted that in this position the plate 25 is also closed. When the bar 27 is retracted so as to open the plate 25, the lever 29 is moved to a position illustrated in broken lines, which results in the opening of the valve 22, permitting water to flow to the nozzles 19. Simultaneously with the movement of ashes into the hopper therefore, water is projecting through the nozzles into the tank and into the path of the ashes so that the latter are thoroughly flushed and quenched. This prevents the deleterious effects of excessive heat upon the side walls of the tank.

In order to provide means for loosening up the ashes in the hopper to prevent undue compacting and to insure a proper flow of ashes towards the discharge opening under all conditions, I provide within the tank and extending transversely thereof a shaft 30. This shaft is journaled in the side walls of the tank and carries at intervals projecting fingers or teeth 31 which, when the shaft is revolved, cause an agitation in the body of ashes within the tank. The extremities of the shaft 30 exterior of the tank are provided with ratchet wheels 32, 32, and loosely suspended from each end of the shaft 65 is an actuating lever 33 which carries in each

instance a pawl 34 resiliently engaging the ratchet 32. It will be obvious that this actuating lever 33 with the pawl 34 and ratchet 32 provides a simple means for rotating the shaft 30 within the hopper. The use of actuating levers is particularly valuable in this respect, in that it provides sufficient leverage to turn the shaft under all conditions.

I claim:

The combination with a furnace, of a hopper adapted to receive ashes direct from under said furnace, adjustable means for controlling the passage of the ashes to the hopper, apparatus associated with the hopper for projecting water to quench the ashes as they enter the hopper, a valve controlling said quenching apparatus, and common actuating means for the said adjustable controlling means and the valve whereby they are opened and closed simultaneously through operation of a single element.

EUGENE HAHN.
